GRADING MACHINE

Nathan Bretholtz, Worcester, Mass., assignor to
 Bretholtz Manufacturing Company, Worcester,
 Mass., a corporation of Massachusetts

Application February 6, 1937, Serial No. 124,391

25 Claims. (Cl. 33—147)

This invention relates to leather grading machines, and more especially to a modified form of the grading machine which I show in my application for patent, Serial No. 714,834, filed March 9, 1934.

In the specification of the above-entitled application, I point out the desirability of edge grading leather blanks, such as soles, and I point out how accurate and practical edge grading may be obtained through my contribution to the art. In the form of my invention described in the said application, I utilize spring pressed moving measuring arms which carry grading rolls which are maintained on the edge of a moving blank through the coaction of a guide foot on each arm with the edge of the blank being graded.

The measuring rolls shown in the said application are of a swiveling type, preferably in the form of casters, and are thus able to follow with ease the contour of the blank being graded. It is mainly through the contribution of swiveling measuring rolls, which are preferably of a caster type, that I am able to obtain the results set forth in the said application. Also, it is mainly in this construction that my contribution to the art, such as evidenced by the Denne patent, No. 1,651,588, resides.

While the invention set forth in the said application supra operates satisfactorily and produces eminently fine results, I find now that I can obtain very fine results also through the use of a simpler mechanism for following the edge contour of a blank to be graded. As already indicated, in my prior application and in such prior art patents as that to Denne, springs are provided to exert a constant force on each of two measuring arms tending to position the measuring rolls carried by said arms inwardly of the blank to be measured or graded. This movement is limited in accordance with the contour of the blank by a guide foot or a guide roll, as is the case in Denne, which rides against the edge of the blank and locates the measuring roll on the edge of the blank.

In the case of the construction shown in my said application, the springs acting on the measuring arms need not be very powerful because the measuring rolls are of a caster type, and very little friction is developed between the rolls and the leather soles because the rolls swivel automatically to a proper angle to reduce friction. The rolls thus follow the edge contour of a blank sole with ease.

In the case of Denne, the rolls are fixed against rotation relatively to the measuring arms with

which the rolls follow the contour of the blank being measured. In a construction of that type, since the friction between a measuring roll and the leather it contacts is relatively great, a relatively heavy spring is required to keep the limiting roll or guide foot against the edge of the blank to follow changes of contour.

Where blanks such as soles are graded, and especially soles having sharp changes in contour, the inertia of the measuring arms will generally be such that when the contour of the sole suddenly changes, the measuring rolls carried by the arms will tend to ride off the sole. In order to overcome this inertia of the arms, and in order to provide the force necessary to move the arms and their rolls laterally relatively to the sole against the considerable friction present, it will be readily understood that extremely heavy springs are required. A further extreme condition also exists which requires an even heavier spring; that is where soles are of a wedge type inclining upward from their edges. Here a fixed roll will have to be moved up a steep incline at the wrong angle to that incline.

Where a sufficiently heavy spring is used to insure the measuring rolls following the sole contour, overcoming both arm inertia, friction, and wedge inclines, a further problem arises in connection with the buckling of the sole at its edge when the sole contour changes in a reverse direction, requiring the outward movement of the measuring roll and the guide foot or guide roll. Where the spring is sufficiently heavy to cause the guide foot or contour following roll to actually follow the contour on inward swings, then on the outward swing the force of this spring must be overcome as well as the friction between the measuring roll and the leather. The force required is so great that unless a very heavy sole is being graded, the leather does not have sufficient stiffness to exert the required force, and thus will buckle under the strain.

It will therefore be quite readily seen that the problem of edge grading, using simply a measuring arm and a roll not of the caster type, is not an easy one to solve. However, I have conceived and developed a grading machine whereby I am able to grade leather blanks such as soles having sharp contour changes, using a non-swiveling and non-caster roll while avoiding any of the defects of the prior art constructions.

In general, my invention comprises the mounting of a guiding roll as I call it, at such an angle relatively to a moving blank that the blank will exert a force on the roll sufficient to move the

roll inwardly relatively to the blank. Where the roll is carried by a measuring arm of the type shown in Denne, or in my application supra, it is quite obvious that the roll will exert a force on the arm and will move the arm in the same manner as though the arm were actuated by a spring. It will be readily appreciated that by adjusting the angle of the roll relatively to the moving sole, either through the particular mounting of the roll on a measuring arm or through the particular mounting of the measuring arm itself, the force exerted by the sole on the roll may be varied within desired limits. It will also be appreciated that if desired, the guiding roll on which the sole acts may serve as a measuring roll as well as a guiding roll.

As a modified form of the invention, I use a pair of rolls mounted in juxtaposed relation, one being the guiding roll, while the other is the measuring roll. I prefer to mount the measuring roll so that it also occupies an angular position relatively to the travel of the moving blank or sole. In this way, both the measuring roll and the guiding roll are capable of better action in the case of soles which are inclined to be thicker just away from their edge and relatively thin at their very edge. The angular relation of the rolls relatively to such a sole causes the rolls to ride up the edge inclines, and thus gives a much better action than would otherwise be possible. It should, of course, be understood that the measuring roll may be placed in any desired angular position without affecting the operation of the guiding roll.

In my invention, I utilize a guide foot which limits the swinging movement imparted to the measuring arm by the guide roll. As a further feature of my invention, I use a rather unusual form of guide foot which conforms to the contour of a base roll over which the blank or sole passes.

Various other detailed features of the construction of my grading machine will be described with reference to the drawings in which two preferred forms of my invention are shown, and such detailed constructions will be set forth in the claims also. Many of the mechanisms which I utilize in the forms of my invention shown in this application, are of the same general class as that shown in my application supra, and will not be described in detail here nor claimed here.

For a detailed description of my invention, I shall now refer to the drawings in which Fig. 1 is an elevation and partial section through a machine incorporating my invention. Fig. 2 is a plan view of the machine construction shown in Fig. 1. Fig. 3 is a section along lines 3—3 of Fig. 1. Fig. 4 is an elevation and partial section of my machine along the lines 4—4 of Fig. 1. Fig. 5 illustrates the relation of my guide foot and my guiding roll relatively to a sole in several positions of the sole. Figs. 6 and 7 are respectively side and front elevations of a modification of my invention. Fig. 8 is a cross section along lines 8—8 of Fig. 6.

Referring now more particularly to the drawings, and especially to Figs. 1 and 2, it will be noted that a pair of main plates 10 and 11 support a series of shafts and cross frame members including bars 12 and 13. Shafts 14, 15 and 16 supported by plates 10 and 11 are continuously driven at related speeds by chains 17 and 18 through sprockets secured to the ends of the shafts 14, 15 and 16. The sprockets are carried

by thimbles 19, 20, 21 and 22, which are pinned to the shafts 14, 15 and 16, as is apparent.

Split driving rolls 23 and 24 are secured for movement integral with the shaft 14, and are equipped with ratchet teeth to better impart movement to a sole moving over the said rolls. Similarly, split rolls 25 and 26 are secured to the shaft 15, while split rolls 27 and 28 are secured to the shaft 16. The rolls 27 and 28 are ratcheted in a manner similar to rolls 23 and 24. 10

A pair of identical sprockets 29 are secured to each of the shafts 14, 15 and 16 in the space between the pairs of split rolls on each of the said shafts, as is probably best shown in Figs. 1 and 2. A chain 30 is mounted on the three sprockets 29 carried on one side of the longitudinal central line of the three shafts 14, 15 and 16. An identical chain 30 is carried by the three sprockets 29 on the other side of the central line of the three shafts. In order to assist in moving a sole through the machine, each of the chains 30 is equipped with a series of prongs 31. These prongs naturally cooperate with the leather of the soles in somewhat the same manner as the ratchet teeth of the rolls 23, 24, 27 and 28. 20

At the front end of the machine (left side in Fig. 1), a pair of split rolls 32 and 33 are carried by a shaft 34 supported on lever arms 35 pivoted to the main plates 10 and 11 on shafts 36 and 37. Through springs 38, the rolls 32 and 33 are maintained in idling and pressing relation to a sole passing through the machine, the pressure on the sole being effective to maintain it in firm contact with the driving rolls 23 and 24. A similar pair of idling pressure rolls 39 and 40 are carried by a shaft 41 and are maintained in pressing relation to driving rolls 27 and 28 through a pair of springs 42, acting similarly to the pair of springs 38.

Supported on main plates 10 and 11 are upper and lower cross bar members 13 and rearward upper and lower cross bar members 12. A presser plate 43 is secured to a pair of rods 44, which rods traverse aligned bores 45 in the cross bar members 12 and 13. Springs 46 are maintained on rods 44 under compression between the upper and lower cross bar members 12 and the upper and lower cross bar members 13, and cooperate with nuts 47 threaded on each of the rods 44, thus urging the rods 44 downwardly. Naturally, the presser plate 43 will also be urged downwardly and into pressing relation to a sole being carried through the machine by the chains 30 and the series of rolls 23—28. 50

From the construction described up to this point, it will be readily seen that once a sole is placed between the idling rolls 32, 33 and the ratchet driving rolls 23, 24, it will be urged through the machine by the cooperation of the remaining driving rolls, the driving chains 30, 60 the prongs 31, and the presser plate 43.

In order to properly center the soles relatively to the machine, I employ an apparatus described in detail and claimed in my application supra. I do not intend to describe the operation of this 65 centering mechanism with regard to the present invention, since naturally, it may be added to this machine without any difficulty. Also, if desired, the soles or blanks may be centered manually, as will be appreciated by those skilled in the art. 70

Carried between the main plates 10 and 11 is a heavy cross bar 50 to which are secured a pair of spaced shafts 51 each of which carries, through suitable ball bearings 52 and 53, a measuring arm 54. The supporting shafts 51 will 75

naturally be spaced on the bar 50 in accordance with the requirements of the remainder of my apparatus, as will be indicated below. For convenience, only one of the measuring arms 54 will be described, since it is understood that the two measuring arms are of course identical, even though they operate oppositely to one another, as is understood by those skilled in this art.

Pivoted at 55 to the measuring arm 54 shown in Fig. 1, is a measuring lever 56 which has secured at its extreme right end a cup member 57 formed internally, as shown at 58, for cooperation with the ball end 59 of a pin 60. A cup 60a covers part of pin 60 and the cup member 57. The pin 60 is in turn pivoted at 61 to a lever 62 secured to the shaft 63, which carries a thickness indicator 64 cooperable with a scale 64a.

Pinned to the shaft 63, as is probably best shown in Fig. 2 at 64 and 65, are a pair of ratchet levers 66 and 67, the indicator 64 being preferably an integral portion of lever 66. A spring 68 secured to the lever 67 tends to rotate the lever and through it the shaft 63, so as to maintain the ball end 69 of the pin 60 within the hollow portion 58 of the cup 57. In this way, the indicator 64 is made to follow the downward movement of cup 58 incidental to increased thickness of a blank or sole being graded.

The end of the ratchet lever 67 is formed with a series of ratchet teeth 69 cooperating with a pawl 70 pivoted at 71 and controlled by a lever 72 in a manner to be described presently, and for a purpose which will also be indicated presently. On the other hand, the ratchet lever 66 is formed at its extreme end with a series of teeth 73 cooperating with a ratchet 74 pivoted at 75 and controlled by a rod 76, for a purpose and in a manner to be explained presently.

The measuring arm 54 has at its forward end a pair of ears 77 traversed by a threaded rod 78 to which are secured a pair of nuts 79 actuated by a compression spring 80 confined between the upper ear 77 and said nuts 79. Naturally, this spring 80 will urge the rod 78 downwardly. At its upper end, the rod 78 is pivoted at 81 to the measuring lever 56, so that the spring 80 therefore tends always to urge the lever 56 in a direction forcing the indicator 64 to a position indicating zero thickness of a sole being measured. A roll 82 is mounted on the shaft 83 carried on the lower end of the rod 78, and this roll is adapted to contact a leather sole passing through the machine. Naturally, this roll 82 will move rod 78 upwardly against spring 80 as the soles which it contacts increase in thickness.

This roll 82, in the modification shown in Fig. 1, has two functions, and I shall now describe one function, which is that of indicating thickness.

It will be obvious that a sole passing through the machine will move the roll 82 upwardly and downwardly together with the rod 78 as the thickness of the leather varies. Naturally, upward movement of the rod 78 will cause rotation of the indicating shaft 63 so as to move the indicator 64 into a position relatively to the dial 64a indicating a particular thickness. The movement in a thickness indicating direction will, of course, be under the influence of spring 68, which rotates the shaft 63 to follow through rod 60 the movement of the measuring lever 56 and its cup 57. Movement in an opposite direction is through the force of spring 80 following the thickness of the sole through rod 78 and roll 82. Naturally, the spring 80 is so much stronger than the spring 68 that the spring 68 is overcome and

indicator 64 will be actuated in a thinness indicating direction when the sole becomes thinner.

Before proceeding to describe the second function of the roll 82 carried by each of the measuring arms 54, I should like to describe a complete measuring cycle of the machine. While doing so, I shall describe also the parts for controlling the rods 72 and 76 which in turn control pawls 70 and 74. A sole first enters the machine when the parts are in the position of Fig. 1. The relation of the sole (identified by the letter S) to the measuring rolls 82 is best shown in Fig. 5. The rolls 82 through the arms 54 are maintained in the initial position of Figs. 4 and 5 relatively to a sole entering the machine, through the operation of the springs 84 connected at 85 to the arms 54 and urging the said arms against adjustable stops 86.

Before the sole strikes rolls 82, it first depresses a lever 87 secured to shaft 88 and lying centrally between the two chains 39 and in a cut-out portion 43a of presser plate 43. The lever 87 is normally maintained in its position of Fig. 1 by a lever 89 secured also to the shaft 88 and spring pressed by spring 90 into the position of Fig. 1 against a stop 91.

The rod 72 already described is pivoted at 92 to the lever 93 integral with lever 89 secured to the shaft 88. In the position of the parts in Fig. 1, the rod 72 is thus maintained by the spring 90 in a position holding the pawl 70 in the teeth 69 of the ratchet lever 67. In this position, the ratchet lever 67, and therefore the shaft 63, are held against movement into a zero thickness indicating position. As a matter of fact, the indicator 64 points to four irons as the thickness indication it last made. Naturally, the depression of lever 87 by a moving sole will rotate shaft 88 clockwise in Fig. 1, thus operating through levers 93 and 72 to move pawl 70 out of teeth 69. This allows the rod 78 carrying roll 82 to move under the influence of spring 80, and moves the indicator 64 into a zero position against the force of spring 68. This places the machine in a position to measure a new sole and start a measuring cycle. The entering sole now contacts the rolls 82 and moves the rolls upwardly in accordance with its thickness, and the said thickness is immediately indicated by the indicator 64.

The thickness of the heel portion of the sole up to the line H in Fig. 5 is not considered of importance and is not a commercial factor. It is the minimum thickness of the remainder of the sole which determines the grade of the sole. Therefore, the indicator 64 is allowed to move freely to show thickness until the roll 82 comes opposite the line H of the sole. At this point, the forward end of the sole will have contacted a further controlling lever 94 mounted in the same relation to chains 39 and presser plate 43 as is the lever 87. The lever 94 is fixed to a shaft 95 which is spring pressed by a spring 96 so as to maintain the lever 94 in its position of Fig. 1, while also maintaining the rod 76 in its position of Fig. 1, it being noted that in this position, the rod 76 holds the pawl 74 away from the ratchet teeth 73 of the ratchet lever 66.

This holding is against the force of spring 97, which is weaker than spring 96, of course. Therefore, the pawl 74 will be maintained in the ratchet teeth 73 when the rod 76 is depressed. The rod 76 will be depressed when the lever 94 is depressed by contact with the sole. The depression of lever 94 will therefore cause the locking of the indicator shaft 63 and indicator 64 against move-

ment in a direction indicating greater thickness. Thereafter, should the sole show a greater thickness by moving the roll 82 upwardly against the force of spring 80, the cup 57 will merely leave the ball end 59 of the pin 60, spring 68 being ineffective to rotate the shaft 63 because of the holding action of the pawl 74 through its cooperation with teeth 73.

The sole continues its movement through the machine, and of course, it is understood that the indicator 64 will be able to move in a direction indicating less thickness, but will be unable to move into a position indicating greater thickness. It now appears quite apparent that if the sole were allowed to pass entirely through the machine and away from under rolls 82, the rolls 82 and the indicator 64 would be moved to zero indicating position under the influence of springs 80. However, before the sole passes from under the rolls 82, it releases the lever 87, allowing the relatively powerful spring 96 to move the pawl 70 into cooperation with teeth 69 of the ratchet lever 67, which immediately locks the indicating hand 64 against movement to a position indicating less thickness of the sole.

Incidentally, this position of the indicator will be maintained after the graded sole leaves the machine and until the following sole once again depresses lever 87, as will be appreciated by those skilled in the art. Also, when the sole passes from under the lever 94, it allows the relatively powerful spring 96 to release the pawl 74 from the ratchet teeth 73, and this releases the indicator 64 for movement to a position of greater thickness under the influence of the next sole to pass through the machine.

While the operation of the machine just described is of the same general nature as the machine described in my application supra, yet many different parts are used and those parts are arranged to contribute better action and to allow for greater compactness of the machine. I shall now describe the second function of the rolls 82, which function has already been referred to. The rolls 82, in addition to being grading or thickness measuring rolls, have the further function of contributing a side movement to the measuring arms 54, so that the rolls 82 will follow the edge contour of the blank to be measured or graded for thickness.

As was indicated in my application supra, edge grading is exceedingly important, since leather soles are sold according to their thickness, and it is the point of minimum thickness along the edge which is of exceeding importance. Those skilled in the art will appreciate that the soles of shoes must be of uniform thickness around the edge, and that unless the soles are graded according to their edge thickness, many difficulties will arise.

In my edge grading machine described in my application supra, and in the edge grading machine of Denne, springs maintain the two measuring arms pressed in a direction, under the control of guide feet, so that the grading rolls ride along the edge of the blank or sole being graded. As I have already indicated, my original application discloses a fine operating machine which has proven a great success. I have already indicated the defects inherent in a simple machine of the Denne type. I shall now show how in my new machine, I maintain the grading rolls in a position along the edge contour of the blank or sole to be graded.

Looking especially at Fig. 4, it will be noticed

that my rolls 82 are set at an angle relatively to the direction of movement of a sole into the machine. In Fig. 5, the angular relation of the rolls 82 relatively to the sole S in the various positions of the sole in the machine is also quite well illustrated diagrammatically, but not with extreme accuracy. Naturally, with the rolls 82 maintained at an angle relatively to the moving sole, the moving sole will exert a force against the rolls 82, urging them toward the center of the moving sole S. This movement will, of course, be controlled by a guide extension 97 which extends downwardly from each measuring arm 54 into an arcuately formed foot 98 conforming to the rolls 25 and 26. It will be quite readily understood that a sole passing through the machine will first strike the two rolls 82 as shown in Fig. 5, and that thereafter, the guide feet 98 will serve to position the rolls 82 with substantially their central portions on the edge of the sole. The arcuate shape of the guide feet 98 is of extreme importance, as will be appreciated and is here emphasized.

The springs 84 which maintain the two arms 54 in their initial position of Fig. 4 are, of course, exceedingly weak, and in themselves would be incapable of keeping the guide feet 98 in contact with the peripheral edge of a sole being graded. The function of the springs is merely to place the arms 54 in the initial position illustrated in Figs. 2, 4 and 5, so that the rolls 82 may be ready for coaction with a sole entering the machine. Thereafter, it is the rolls 82 which keep the guide feet 98 against the sole, so that the rolls may measure or grade the edge of the sole.

It will also be appreciated that the only force that the feet 98 have to overcome in swinging the arms outwardly is the friction between the rolls 82 and the sole tending to move the rolls 82 centrally of the sole. No powerful arm swinging springs are present to be overcome, as in the prior art. The advantages of this relation of the parts have been explained already, and will now appear more clear.

The angular position of the rolls 82 relatively to the sole travel is maintained by fixing the shaft 78 on which each roll 82 is mounted against rotation relatively to its particular arm 54. It will also be appreciated, of course, that the measuring arms 54 may be mounted on pivot shafts 51, spaced somewhat differently from the spacing of the pivot shafts 51 shown in my application, so that the angle between the rolls 82 and the sole passing through the machine will be maintained because of this spacing, rather than because of the angularity of the rolls relatively to the arms themselves. Naturally, it is quite possible to vary the form of my invention in many ways while utilizing the basic principle of the angular rolls receiving movement from the moving sole. This should be borne in mind in considering the scope of the monopoly I claim.

As a further modification of my invention, I utilize a pair of rolls on each arm 54, one of the rolls having the same function as the roll 82 in Fig. 4, in so far as controlling the movement of arm 54 is concerned. The other roll is used only for grading or measuring the sole. By using two rolls instead of one, I am able to have a relatively heavy spring operating the moving or guiding roll, while the grading roll may be operated with a much lighter spring, as will of course be appreciated, it having no function other than grading.

This modification of my invention is illustrated in Figs. 6, 7 and 8. There it will be noticed that the arm 54 also has the ears 77 in which is

guided a shaft 100 and a concentric hollow threaded shaft 101. The hollow threaded shaft 101 has secured thereon a pair of interlocking nuts 102 which cooperate with a spring 103 abutting the upper ear 77, thus acting to press the shaft downwardly. At its lower end, it has secured a roll 104, which is the moving or guiding roll and which operates in a manner identical to the roll 82 of the modification of Fig. 1, in that it tends always to move the arm 54 to a central portion of a blank being graded. A guide foot 98 of the same form as that illustrated in Fig. 1 limits this movement through engagement with the edge of the sole being graded. The solid rod 100 traversing the hollow rod 101 extends upwardly through the ear 77 and is secured by pivot 81 to a measuring lever 56, in the same manner as the rod 78 is secured to the measuring lever 56 in the modification of Fig. 1.

20 The rod 100 extends downwardly and has secured at its lower end through a shaft 105, a grading roll 106 which operates to grade a sole in much the same manner as the roll 82 of the modification of Fig. 1.

25 The angular relation of the rolls 104 and 106 is probably best illustrated in Fig. 8, and I prefer to maintain this relationship. However, it is not entirely necessary that the roll 106 be mounted at an angle relatively to a moving sole. 30 It is best, however, that this be done, since it lessens the frictional resistance to the movement of the roll 106, especially where leather soles are measured which incline upwardly from their edge.

35 For maintaining the roll 106 in contact with the sole being graded, I use a relatively light spring 107, thus obtaining quite a desirable result, as will be readily appreciated.

Having now described two modifications of my invention, I should like to point out that I consider my contribution to the art to be quite broad, and of exceeding importance, and I do not wish to be limited in the monopoly to be granted me, except as may be required by the state of the art.

I claim:

40 1. In a machine of the class described, a measuring arm, means mounting said arm for movement, and means for moving said arm in response to the changing contour of a moving blank to be measured comprising an element in contact with the blank and tending through said contact to move said arm inwardly of the blank and a second element in contact with the periphery of the blank limiting said inward movement in accordance with the contour of the blank.

45 2. In a machine of the class described, a measuring arm, means mounting said arm for swinging movement, and means for swinging said arm in response to the changing contour of a moving blank to be measured comprising an element in contact with the surface of the blank and tending through said contact to swing said arm inwardly of the blank and a second element in contact with the periphery of the blank limiting said swinging movement in accordance with the contour of the blank.

50 3. In a machine of the class described, a measuring arm, means mounting said arm for swinging movement, and means movable with said measuring arm and maintained in contact with a moving blank to be measured and actuated by said contact with the blank for swinging said arm in each of opposite directions in accordance with changes in the contour of the moving blank.

55 4. In a machine of the class described, a measuring arm, means mounting said arm for swing-

ing movement, a roll carried by said swinging arm for contact with a moving blank to be measured, a shaft on which said roll is mounted at a predetermined angle relatively to the direction of movement of said blank, the contact of said moving blank relatively to the roll tending to swing the arm inwardly of the blank.

60 5. In a machine of the class described, a measuring arm, means mounting said arm for swinging movement, a roll carried by said swinging arm for contact with a moving blank to be measured, means mounting said roll at a predetermined angle relatively to the direction of movement of said blank, the contact of said blank relatively to the roll tending to swing the arm inwardly of the blank, and a guide foot in contact with the blank periphery for limiting this inward swinging movement in accordance with the blank contour.

65 6. In a machine of the class described, a measuring arm, means mounting said arm for swinging movement, a roll carried by said swinging arm for contact with a moving blank to be measured, means mounting said roll at a predetermined angle relatively to the direction of movement of said blank, the contact of said blank relatively to the roll tending to swing the arm inwardly of the blank, the said angle being such that the rate of inward swing contributed by said roll will be greater than any curvature of said blank, whereby said roll will not roll off the blank upon a sharp change in its contour, and a guide foot in contact with the blank periphery for limiting the said inward swinging movement contributed by said roll in accordance with the edge contour of the blank.

70 7. In a machine of the class described, a measuring arm, means mounting said arm for swinging movement, a roll carried by said swinging arm for contact with a moving blank to be measured, means securing said roll at a predetermined angle relatively to the direction of movement of said blank, the contact of said blank relatively to the roll tending to swing the arm inwardly of the blank, a guide foot in contact with the blank periphery for limiting this inward swinging movement in accordance with the blank contour, means mounting said roll for vertical measuring movement relatively to said swinging arm in accordance with changes in the thickness of the said blank contacted by said roll, and indicating mechanism actuated by said roll as it moves in accordance with changes in the thickness of said blank.

75 8. In a machine of the class described, a measuring arm, means mounting said arm for swinging movement, a roll carried by said swinging arm for contact with a moving blank to be measured, means mounting said roll at a predetermined angle relatively to the direction of movement of said blank so that the contact of the moving blank relatively to the roll will tend to swing the roll and its arm inwardly of the moving blank.

80 9. In a machine of the class described, a measuring arm, means mounting said arm for swinging movement, a roll carried by said swinging arm for contact with a moving blank to be measured, means mounting said roll at a predetermined angle relatively to the direction of movement of said blank so that the contact of the moving blank relatively to the roll will tend to swing the roll and its arm inwardly of the moving blank, and a guide foot in contact with the blank periphery for limiting the inward

swinging movement in accordance with the blank contour.

10. In a machine of the class described, a measuring arm, means mounting said arm for swinging movement, a measuring roll mounted for vertical measuring movement relatively to said arm and adapted to receive measuring movement when contacted by a moving blank to be measured, means mounting said roll at such an angle relatively to the direction of movement of said blank that contact of the roll with the blank will tend to swing said roll and arm inwardly of the blank, and means for limiting the said inward swinging movement to an extent whereby 15 said roll remains always in a predetermined relation to the edge of the blank to be measured.

11. In a machine of the class described, a measuring arm, means mounting said arm for swinging movement about a fixed axis, a measuring roll mounted for vertical measuring movement relatively to said arm and adapted to receive measuring movement when contacted by a moving blank to be measured, means mounting said roll at such a position relatively to the said 25 fixed axis of said arm and at such an angle relatively to the direction of movement of said blank that contact of the roll with the blank will tend to swing said roll and arm inwardly of the blank, and means for limiting the said inward swinging 30 movement to an extent whereby said roll remains always in a predetermined relation to the edge of the blank to be measured.

12. In a machine of the class described, a measuring arm, means mounting said arm for swinging movement, means for swinging said arm in response to the changing contour of a moving blank to be measured comprising an element in contact with the blank and tending through said contact to swing said arm inwardly of the blank 40 and a second element in contact with the periphery of the blank limiting said swinging movement in accordance with the contour of the blank, a measuring element carried by said arm for vertical measuring movement relatively to 45 said arm and adapted to receive measuring movement when contacted by said moving blank, said arm swinging means cooperating to maintain the said measuring element in predetermined relation to the edge of the said blank.

13. In a machine of the class described, a measuring arm, means mounting said arm for movement, means movable with said measuring arm and maintained in contact with a moving blank to be measured and actuated through said contact with the blank for moving said arm in opposite directions in accordance with changes in the contour of the said moving blank, a measuring element carried by said arm for vertical measuring movement relatively to said arm 60 and adapted to receive measuring movement when contacted by said moving blank, said arm moving means cooperating to maintain the said measuring element in predetermined relation to the edge of the said blank.

14. In a machine of the class described, a measuring arm, means mounting said arm for movement, a roll carried by said arm for contact with a moving blank to be measured, means mounting said roll at a predetermined angle 70 relatively to the direction of movement of said blank so that the contact of the moving blank relatively to the roll will tend to move the roll and its arm inwardly of the moving blank, a measuring element carried by said arm for vertical measuring movement relatively to said arm 75

and adapted to receive measuring movement when contacted by said moving blank, said arm moving means cooperating to maintain the said measuring element in predetermined relation to the edge of the said blank.

15. In a machine of the class described, a measuring arm, means mounting said arm for swinging movement, arm swinging means including a guide roll carried by said swinging arm for contact with a moving blank to be measured, said guide roll being mounted at a predetermined angle relatively to the direction of movement of said blank so that the contact of the moving blank relatively to the roll will tend to swing the roll and its arm inwardly of the moving blank, a measuring roll carried by said arm for vertical measuring movement relatively to said arm and adapted to receive measuring movement when contacted by said moving blank, said arm swinging means maintaining the said measuring roll in predetermined relation to the edge of the said blank, the said measuring roll being mounted at the same angle as said guide roll.

16. In a machine of the class described, a measuring arm, means mounting said arm for swinging movement, a guide roll carried by said swinging arm for contact with a moving blank to be measured, means mounting said guide roll at a predetermined angle relatively to the direction of movement of said blank so that the contact of the moving blank relatively to the roll will tend to swing the roll and its arm inwardly of the moving blank, a guide foot in contact with the blank periphery for limiting the inward swinging movement in accordance with the blank 35 contour, a measuring roll carried by said arm for vertical measuring movement relatively to said arm and adapted to receive measuring movement when contacted by said moving blank, said guide roll and guide foot cooperating to maintain the 40 said measuring roll in predetermined relation to the edge of the said blank.

17. In a machine of the class described, a measuring arm, means mounting said arm for swinging movement, a guide roll carried by said 45 swinging arm for contact with the relatively flat surface of a moving blank to be measured, a spring of relatively great strength urging said guide roll against the surface of said moving blank, means securing said guide roll at a predetermined angle relatively to the direction of movement of said blank so that the contact of the moving blank relatively to the said guide roll will tend to swing said guide roll and its arm inwardly of the moving blank, a guide foot for limiting 55 said swinging movement in accordance with the blank contour, a measuring roll carried by said arm for vertical measuring movement relatively to said arm and adapted to receive measuring movement when contacted by said moving blank, a relatively weak spring urging said measuring roll against said moving blank, said guide roll and guide foot cooperating to maintain the said measuring roll in predetermined relation to the 60 edge of the said blank.

18. In a machine of the class described, a measuring arm, means mounting said arm for swinging movement, means for swinging said arm in response to the changing contour of a 70 moving blank to be measured comprising a guide foot in contact with the periphery of the blank, a base roll over which the moving blank passes to be measured, said guide foot being formed to conform substantially to the circumference of 75

the base roll whereby to facilitate its proper contact with the moving blank.

19. In a machine of the class described, measuring elements adapted to move an indicator in accordance with variations in thickness of a moving blank, an indicator located at a point on said machine above the plane of the moving blank, a thinness locking means for locking the indicator against movement in a direction indicating zero thickness, a thickness locking means for locking the indicator against movement in a direction indicating greater thickness, base means over which said blank moves for measurement by said measuring elements, trigger levers protruding between said base means for depression by said moving blank, and means of connection extending transversely and then upwardly from said trigger levers to said thinness and thickness locking means.

20. In a machine of the class described, a measuring arm mounted for pivotal swinging movement on a vertical axis, a pair of vertical shafts mounted on said arm for vertical sliding movement, a roll at the end of each shaft, a spring for each of said shafts pressing said rolls downwardly and against a moving blank to be measured, means whereby one of said shafts is held so that its roll is at such a predetermined angle relatively to the direction of movement of a blank through the machine that its contact with said blank tends to swing said roll, its shaft and said arm, inwardly of the blank, a guide foot extending from said arm and limiting the said swinging movement to an extent maintaining the roll carried by the other shaft directly on the edge of the moving blank, and measuring means actuated by the movement imparted to said last named roll and its shaft through variations in the edge thickness of the blank.

21. In a machine of the class described, a measuring arm mounted for pivotal swinging movement on a vertical axis, a pair of vertical concentric shafts mounted on said arm for vertical sliding movement, a roll at the end of each shaft, a spring for each of said shafts pressing said rolls downwardly and against a moving blank to be measured, means whereby the outer of said concentric shafts is held so that its roll is at such a predetermined angle relatively to the direction of movement of a blank through the machine that its contact with said blank tends to swing said roll, its shaft and said arm, inwardly of the blank, a guide foot extending from said arm and limiting the said swinging movement to an extent maintaining the roll carried by the inner shaft with its vertical center directly on

the edge of the moving blank, the said shaft and roll being held at the same angle as the first roll and its shaft, and measuring means actuated by the movement imparted to said last named roll and its shaft through variations in the edge thickness of the blank.

22. Measuring mechanism for following the contour of a blank to be measured, comprising means in contact with the surface of the blank and urged through said contact to a position inwardly of the blank as the measuring mechanism moves relatively to the blank, and means limiting the said movement in accordance with the edge contour of the blank.

23. Measuring mechanism for following the contour of a blank to be measured, comprising a roll in contact with the surface of the blank, the roll being at a predetermined angle relatively to said blank whereby it is urged through contact with said blank to a position inwardly of the blank as the measuring mechanism moves relatively to the blank, and means limiting the said movement in accordance with the edge contour of the blank.

24. In a machine of the class described, a series of shafts, pairs of split driving rolls on each of said shafts leaving a space medially of the longitudinal axis of the machine unoccupied by said rolls, sprockets on the shaft portions in said space, driving chains on said sprockets for assisting said rolls in forcing a blank through said machine, a presser plate overlying the said chains, a slot in the under side of the said presser plate, and controlling trigger levers extending from under said driving rolls into the said slot for actuation by a blank passing through the said machine.

25. In a machine of the class described, measuring elements adapted to move an indicator in accordance with variations in thickness of a moving blank, an indicator located at a point on said machine above the plane of the moving blank, a thinness locking means for locking the indicator against movement in a direction indicating zero thickness, a thickness locking means for locking the indicator against movement in a direction indicating greater thickness, base means over which said blank moves for measurement by said measuring elements, trigger levers protruding through an opening in said base means for depression by said moving blank, and means extending sidewise under said base means from said trigger levers to a position beyond the edge of the blank for actuating said thinness and thickness locking means.
